US00D857191S

(12) **United States Design Patent** (10) **Patent No.:** **US D857,191 S**
(45) **Date of Patent:** **** Aug. 20, 2019**

(54) **WEARABLE DRUG DELIVERY DEVICE**

(71) Applicant: **Becton, Dickinson and Company**,
Franklin Lakes, NJ (US)

(72) Inventors: **Charles George Hwang**, Wellesley,
MA (US); **John Prudden**, Manchester,
MA (US); **Christopher Kovalchick**,
Bedford, MA (US); **Russell Cole**, River
Vale, NJ (US); **Andrew Allegretti**,
Edgewater, NJ (US); **Jeffrey Reed**,
Minden, NE (US); **Nir Swenson**,
Somerville, MA (US); **Gail Siewiorek**,
Winchester, MA (US); **Joseph
Iskandar**, Brighton, MA (US);
Alessandro Pizzochero, Chelmsford,
MA (US); **J. Richard Gyory**, Sudbury,
MA (US); **Justin Cumming**, Arlington,
MA (US); **Kurt Maw**, Salem, MA (US)

(73) Assignee: **Becton, Dickinson and Company**,
Franklin Lakes, NJ (US)

(**) Term: **15 Years**

(21) Appl. No.: **29/552,312**

(22) Filed: **Jan. 21, 2016**

(51) LOC (12) Cl. **24-02**

(52) U.S. Cl.

USPC **D24/112**

CLAIM

The ornamental design for a wearable drug delivery device, as shown and described.

DESCRIPTION

FIG. 1 is a top perspective view of a wearable drug delivery device showing our new design;

FIG. 2 is a bottom perspective view thereof;

FIG. 3 is a top plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a bottom plan view thereof.
